[57] **CLAIM**

The ornamental design for a front control panel for a
microprocessor, as shown and described.

DESCRIPTION

FIG. 1 is a front elevational view of a front control panel for a microprocessor showing my new design;
FIG. 2 is a right side view thereof;
FIG. 3 is a left side view thereof;
FIG. 4 is a top view thereof; and,
FIG. 5 is a bottom view thereof.

The broken lines are shown in the views for illustrative
purposes only and form no part of the claimed design
and the bold horizontal stripes in FIG. 1 represent a
conventional pattern.

FIG. 1

FIG. 2

FIG. 3

FIG. 4
